RECTIFIER RELAY CIRCUIT

Application filed July 31, 1926, Serial No. 126,196, and in Germany September 15, 1925.

This invention relates to electron discharge rectifiers and particularly to circuits employing such devices for operating relays by voice frequency or other alternating current waves.

5 An object of the invention is to improve the operation of electron discharge rectifiers, and particularly their sensitivity.

Another object of this invention is to control the operating periods of the relays in 10 such circuits.

Relays operated by voice or other signaling currents in the line are employed in echo suppressors, reaction suppressors, voice operated repeaters and the like. In such circuits it is the general practice to employ 15 vacuum tube amplifier-rectifiers for operating the relays. Generally these circuits are so arranged that the amplified speech currents act on a rectifier tube operating at the lower 20 bend of the anode current characteristic curve. The direct current component of the anode current produced actuates a relay which controls corresponding contacts. With 25 such a circuit it is necessary to use a grid battery which is considerably larger than that required for ordinary repeaters, in order to bias the grid of the rectifier sufficiently negative. It is also necessary to use relatively sensitive relays since the rectified anode 30 current attainable is small because it only consists of the positive half waves of the sinusoidal currents impressed on the grid circuit.

In accordance with a feature of this invention, proper operation of the rectifier-relay circuit is attained using a grid battery of ordinary size and a relay of comparatively low sensitivity, by positively biasing the grid of the rectifier tube and using a condenser 35 and resistance in parallel in the grid circuit and a coil of large inductance in the anode circuit of the rectifier tube. This arrangement has the additional advantage that the actuating and releasing periods of the associated relay can be controlled by means of 40 the condenser and resistance as explained hereinafter.

Instead of working on the lower bend of the characteristic curve, a tube connected 45 in the manner of this invention works on

the upper portion of the curve. In the normal condition, i. e. in the absence of an alternating current wave impressed upon the grid, the full emission current flows in the relay connected in the anode circuit due to 55 the fact that the grid is positively biased. When an alternating current wave is impressed upon the grid circuit the effect is to reduce the current in the anode circuit causing the relay to release. This reduction in 60 anode current is caused by the reduction in the grid potential produced by the speech currents which, due to the bend in the grid current characteristic of the tube, cause an increase in the grid current which charges the 65 condenser and increases the drop across the resistance in shunt thereto thus decreasing the potential of the grid. After the cessation of the alternating current the anode current can only rise again to the normal 70 value required to actuate the relay after the discharge of the condenser. The charging and discharging periods of the condenser may, however, be readily controlled by proportioning the values of the condenser and 75 resistance in shunt thereto to consequently control the actuating and releasing periods of the relay.

This invention can be more readily understood by reference to the following detailed 80 description in connection with the drawing which shows one embodiment thereof.

The drawing shows an amplifying tube 3 and a rectifying tube 4 connected in tandem through an interstage transformer 5. The 85 controlling speech currents are supplied through the resistance network 6 to the input transformer 7. The cathodes 8 and 9 of the tubes 3 and 4 respectively are connected in series to the battery 10 for receiving heating current therefrom. A ballast lamp 19 is included in the cathode heating circuit. The grid 11 of the tube 3 is connected through the secondary of the transformer 7 to the negative terminal of battery 10 to give it a 90 negative bias with respect to the cathode 8. The grid 12 of the tube 9 is connected to the positive side of the battery 10 to positively 95 bias it with respect to the cathode 9. The condenser 13 and resistance 14 are connected 100

in parallel with one another in the grid circuit of tube 4. Battery 15 serves to supply space current to both tubes. The relay 16 is connected in series with the high inductance choke coil 17 in the anode circuit of the tube 4. The circuit operates as explained above, the armature 18 of the relay 16 being held out of contact in the normal condition. When voice currents are impressed upon the circuit the current in the relay winding is reduced, releasing the armature 18.

Since the impedance of the coil 17 is high compared to the impedance of the relay winding the latter may be shunted by a condenser if desired.

15 What is claimed is:

1. A rectifier-relay circuit comprising an electron discharge device having an anode, a cathode, a control electrode, and circuits therefor, a circuit-closing electro-magnetic relay connected in the anode circuit of said device, means for positively biasing said control electrode sufficiently to cause substantially saturation current to flow in said anode circuit to energize said relay, a resistance and 20 a condenser in parallel in the control electrode circuit of said device for developing a negative biasing potential on said control electrode when control waves are impressed on the control electrode circuit, and high 25 impedance means included in said anode circuit in series with said relay, said parallel resistance and condenser being proportioned with respect to the other elements of the circuit to control the actuating and releasing 30 periods of said relay.

35 2. A voice operated rectifier-relay circuit comprising a space discharge device having a cathode, an anode, a control electrode, and circuits therefor, a circuit-closing electro-magnetic relay connected in the anode circuit of said device, means for applying a positive biasing potential to said control electrode of sufficient value to cause normally 40 substantially saturation current to flow in 45 said anode circuit to energize said relay, means for impressing voice current waves on the control electrode circuit, a condenser and a resistance connected in parallel in said control electrode circuit for developing a negative 50 biasing potential on said control electrode when voice current waves are impressed on said control electrode circuit, and a choke coil of high inductance included in series 55 with said relay in said anode circuit, said parallel resistance and condenser and the inductance of said choke coil being relatively proportioned so as to regulate the actuating and releasing periods of said relay.

60 3. A voice operated relay circuit comprising an electric discharge device having cathode, anode and grid elements, a cathode-anode or output circuit containing a relay, a grid circuit containing a source of voltage biasing the grid positive such that in the absence 65 of voice currents in the grid circuit

substantially saturation current flows in the anode circuit and through the relay causing it to hold its armature attracted, said grid circuit also including a permanently connected parallel condenser-resistance combination proportioned to cause the relay to release 70 upon application of speech currents to the grid and to remain released during continuous application of such speech currents and again to attract its armature quickly upon cessation of the speech currents.

75 In witness whereof, I hereunto subscribe my name this 8th day of July A. D., 1926.
